United States Patent Office.

ALBERT E. POWERS, OF LANSINGBURG, NEW YORK, ASSIGNOR TO HIMSELF, DEBORAH POWERS, AND NATHANIEL B. POWERS, OF THE SAME PLACE.

Design No. 2,801, dated October 15, 1867.

DESIGN FOR FLOOR-CLOTH PATTERN.

The Schedule referred to in these Letters Patent and making part of the same.

TO ALL WHOM IT MAY CONCERN:

Be it known that I, ALBERT E. POWERS, of the village of Lansingburg, county of Rensselaer, and State of New York, have invented or produced a new and original Design for Floor Oil-Cloths, the details of which are fully shown upon the drawings which accompany this specification, which are hereby declared to be a part of the same.

And what is claimed as my invention, and is desired to be secured by Letters Patent of the United States, is—

The pattern or design for floor oil-cloths or other fabrics, shown upon the aforesaid drawings, whether used in the same or in other colorings.

A. E. POWERS.
